UNITED STATES PATENT OFFICE.

PATRICK HENRY FRANK, OF ZAMBOANGA, PHILIPPINE ISLANDS.

HEMP-STRIPPING MACHINE.

Application filed June 5, 1920. Serial No. 386,722.

To all whom it may concern:

Be it known that I, PATRICK HENRY FRANK, a citizen of the United States, and a resident of Zamboanga, Philippine Islands, have invented a new and useful Improvement in Hemp-Stripping Machines, of which the following is a specification.

My present invention relates generally to machines for stripping hemp and particularly to a machine whereby the operation of pulling hemp leaves under stripping knives may be accomplished mechanically and the great strain of performing this operation manually, avoided in this 15 way.

The primary object of my invention is the provision of a machine of sufficient strength and durability to effectively accomplish the desired operation, and at the same time one which is capable of ready transportation from one part to another about a plantation.

It is a well-known fact that at the present time hemp stripping operations are carried 25 out by hand, the butts of the leaves being grasped and drawn under knives held by adjustable pressure.

It is furthermore well known that this is an extremely laborious operation frequently impairing and ruining operators' health through the strains incident to manual manipulation of the leaves, all of which 30 my invention by substituting mechanical means, avoids.

35 In the accompanying drawings illustrating my invention and forming a part of this application,

Figure 1 is a side elevation,

Figure 2 is a front elevation,

40 Figure 3 is a top plan view of the carriage, on an enlarged scale,

Figure 4 is a side view thereof,

Figure 5 is a provisional end elevation of the carriage,

45 Figure 6 is a vertical cross section through the main frame, on an enlarged scale,

Figure 7 is a detail section through one of the carriage supported clamps,

50 Figure 8 is an enlarged side view of certain portions to be hereinafter specifically referred to.

Referring now to these figures, the main frame of my improved apparatus is mounted on lower side runners 10, and includes a series of uprights 11, certain of which are inclined as seen in Figure 6. The upper

ends of these uprights are connected by cross bars 12 which support parallel lengthwise rails 13, each of which rails is formed of angle bars as most clearly shown in Figure 6 to receive and partially enclose rollers 14 rotatably mounted at the lower side portions of a lengthwise movable carriage 15.

To opposite ends of the carriage 15 are secured the opposite ends of cables or other flexible operating connections 16 and 17 extending lengthwise between the rails 13 and downwardly and inwardly around pulleys 18 and 19 at the relatively opposite ends of the main frame, the lower extensions of these flexible operating connections leading to pulleys 20 and 21, to which they are attached and around which they are adapted to wind and unwind. These pulleys are respectively mounted upon shafts 22 and 23, having sprocket wheels connected by a sprocket chain 24 and each provided with a suitable clutch engageable with its normally loose cable actuating drum or pulley. The clutches of the two shafts of which the clutch of shaft 22 is indicated at 25 in Figure 1, are controlled through clutch actuating levers 26 and 27 having crank connections with the lower ends of rock shafts 28 and 29, the latter of which upstand at relatively opposite sides of the main frame and also upon relatively opposite sides of the center of the frame.

These rock shafts have angular arms 30 beneath the rails 13, to which lengthwise control rods 31 are connected. These control rods extend lengthwise of the main frame and upon adjacent relatively opposite sides thereof and toward relatively opposite ends where they are connected to operating levers 32 for starting the operation at either end of the main frame.

At each end the main frame has a stationary transverse knife block 33, above which is a transversely disposed vertically movable stripping knife 34, the latter removably bolted to the upper cross piece 35 of a knife supporting frame including depending side bars 36 connected at their lower ends by a cross bar 37. This latter cross bar 37 is engaged by the free end of a spring 38 adjustable below the respective end of the main frame in connection with an upright 39 and anchored at one end to an upright 40. The spring 38 supplies the tension which in the effective position of the stripping knife 34 holds the latter down-

wardly and with the required tension, upon the knife block 33 or more particularly upon a hemp leaf disposed between the stripping blade and the knife block.

5 To certain of the end uprights 11 at each end of the main frame, is pivoted a foot treadle 41 connected by a rod 42 with one end of the lever 43 whose opposite end engages the lower cross bar 37 of the knife frame through a link 44 so that by depressing the foot treadle 41, the knife frame and consequently the stripping blade 34, may be elevated to permit of passage of a hemp leaf partly beneath the same and sufficiently far 10 for it to be grasped by the respective clamp of the carriage 15 to be hereinafter described.

At each end, the carriage 15 is provided with notches 45 in its upper side bars 46, 20 receiving the ends of a transverse shaft 47 journaled through the carriage uprights 15 and also extending through and secured to the upper ends of the side portions 48 of a clamp including a lower cross bar 49 to 25 which the side portions 48 are secured having a lower toothed surface 50 adapted for cooperation in clamping engagement with an end cross piece 51 as the clamp swings downwardly and outwardly, on account of 30 its shape as shown. Each shaft 47 is connected intermediate its ends to links 52 and an arm 53, with a cross shaft 54 having a depending side arm 55, it being noted that the two arms 55 are located at relatively 35 opposite sides of the carriage for engagement at relatively opposite ends of the main frame, by stop pieces 56 located adjacent to the stripping knives so that upon engagement of these stop pieces with the lower end 40 of the respective side arm, swinging movement of the latter will be transmitted through the respective shaft 54 and the connections 52 and 53, to the respective clamp actuating shaft 47 so as to swing the clamp 45 upwardly and rearwardly and in this way open the clamp for the reception of the leaf butt after the latter has been shifted beneath the respective stripping blade.

Figures 1, 3 and 4 show both clamps 50 closed, with the triggers in inactive positions and, due to the location of the arms 55 and their respective stop pieces 56 at relatively opposite ends of the carriage 15 and the frame as previously mentioned, it 55 becomes obvious that the carriage of Figure 1 will complete its movement to the right hand end of the frame before the stop piece 56 operates to open the left jaw of the carriage or in other words that jaw which 60 will in operation carry the material when the carriage is proceeding to the right. In its next movement the carriage travels to the left end of the frame with the material engaged under the right clamp of the carriage 65 and proceeds until this latter clamp

is released by the stop piece at the left end of the frame located upon the far side of the frame in Figure 1.

It will be noted that each of the side arms 55 through which the clamps are thus automatically opened, carries a clamp engaging trigger 57 which slips beneath and engages the clamp when the latter is raised inwardly and thus opened and holds it in such position while the leaf is placed beneath the clamp and until downward movement of a trigger releasing bar 58 whose upper angular end is movable downwardly to depress and release the trigger against the tension of the spring 57^a of the latter. These trigger releasing bars 58 are mounted adjacent to the knife blocks 33 and each thereof is also mounted adjacent to one of the operating levers 32 and is connected at its lower end thereto by a crank 59 so that when the operating lever is pulled toward the end of the frame, the bar 58 is shifted downwardly to release the respective leaf engaging clamp of the carriage 15 simultaneously with movement of the corresponding connecting rod 31 so as to shift one of the pulley clutches into active position. For instance in Figure 8 the lever 32 is thrown to the left when the carriage of Figure 1 stops at the right hand end of the main frame, and in this movement the bar 58 is shifted upwardly at the rear of the right hand clamp of the carriage to engage trigger 57 at this time holding the right hand clamp in upper released position. When the material has been passed beneath the stripping knife and into the clamp of the carriage and the latter is ready to start upon its movement to the left end of the frame, the lever 32 is shifted to the right during which movement the clutches are properly manipulated for such movement of the carriage and also during which movement the bar 58 is shifted downwardly so as to engage and release the respective trigger 57 permitting the clamp to actively engage and hold the material.

Thus when the lever 32 at the right end of the main frame in Figure 1 is moved to operative position the clutch of pulley 20 is shifted to engaged position and power is thus communicated from shaft 22 to the pulley 20 so as to wind the flexible connection 16 onto the drum or pulley and thus draw the carriage 15 toward the left-hand end of the machine. In this way the hemp leaf which has just been effectively engaged by the release and operative movement of the respective carriage clutch, will be drawn beneath the stripping knife and will move with the carriage toward the left-hand end of the frame and until it approaches the left end of the machine, where the clamp will be released upon engagement with the respective stop piece 56, the carriage at or about the same time striking

an upright 60, which each of the actuating rods 31 carries, so that the clutch of pulley 20 will be shifted and released, stopping the movement of the carriage adjacent to the left-hand end of the machine, with the previously drawn and stripped hemp leaf in released position and with both of its clamps elevated and inactive from a previous operation, ready for the introduction 10 of a hemp leaf.

It is understood that upon the introduction of each hemp leaf the respective foot treadle 41 is depressed to elevate the stripping knife, and while it is apparent a 15 considerable portion of the hemp leaf is required to be extended inwardly beyond the knife in order that it may be engaged with the carriage, it should be understood that in connection with the mechanical stripping 20 of hemp leaves they are originally cut from the plants somewhat longer than they are at present cut for hand stripping so as to give the extra length required.

The shaft 22 is driven and may be 25 extended between two hemp stripping machines as seen in Figure 2 where shaft 22 is shown provided with fast and loose pulleys 61 and 62 for the reception of a belt and is also shown provided with a 30 heavy fly wheel 63 the purpose of which is to maintain a steady pull and produce clean even fiber, vibration or jerky motion being very harmful.

I claim:—

35 1. A hemp stripping machine comprising a frame, adjustable stripping knives at the opposite ends of the frame, a carriage having movement lengthwise of the frame between the said knives, leaf holding clamps 40 carried by the ends of the carriage and each of which is swingable toward its respective end of the carriage into active position when movement of the carriage is started in one direction and means whereby to 45 shift each of the clamps into inactive position at the end of the corresponding movement of the carriage, as described.

2. A hemp stripping machine comprising 50 a main frame, knife frames adjustable vertically at opposite ends of the frame, stripping knives in said latter frames, a carriage movable in the frame between said knives and having leaf holding clamps, actuating means for moving the carriage in relatively 55 opposite directions, manually actuated connections for independently shifting the said carriage moving means into active position, connections actuated by the carriage for shifting said carriage moving means into 60 inactive position, an adjustable controlling spring for each knife frame, and manually actuated means having engagement with the said knife frames for shifting the same against the tension of their springs.

65 3. A hemp stripping machine comprising

a frame, a carriage movable in the frame, leaf engaging clamps at opposite ends of the frame, each clamp being swingable toward its respective end of the carriage into active position, clamp releasing arms 70 swingable at opposite sides of the carriage, link connections between each arm and its respective clamp to swing the latter to inactive position, means to hold the same in inactive position, and means supported on 75 the main frame for actuating the arms during movement of the carriage.

4. A hemp stripping machine comprising a frame, a carriage movable in the frame, leaf engaging clamps at opposite ends of 80 the frame, each clamp being swingable toward its respective end of the carriage into active position, clamp releasing arms swingable at opposite sides of the carriage, link connections between each arm and its respective clamp to swing the latter to inactive 85 position, means to hold the same in inactive position, and means supported on the main frame for actuating the arms during movement of the carriage, reversible means for 90 actuating the carriage in its movement, and manually actuated means for controlling the carriage actuating means, having means movable therewith for releasing the said clamp holding means. 95

5. A hemp stripping machine including a lengthwise movable carriage, stripping knives between which the carriage moves, a pair of transverse shafts, gearing connecting said shafts, means for driving one 100 of the shafts, pulleys loosely mounted on said shafts, flexible connections wound on and leading from said pulleys to opposite ends of the carriage, clutches for the pulleys arranged and connected to engage one pulley 105 while the other one is disengaged, levers controlling said clutches, clamps on the carriage at its opposite ends, means to release said clamps at the opposite ends of movement of the carriage, means to hold 110 the clamps in inactive position when released, and means having connection with the clutch control levers for releasing said clamp holding means when movement of the carriage is started. 115

6. In a machine of the class described the combination of a main raceway having at each end thereof a set of decorticating tools, a carriage supported upon said raceway, means for reciprocating said carriage toward 120 and from said decorticating tools, and stock gripping jaws on each end of said carriage arranged so as to draw a piece of stock through the space between the decorticating tools of one set as the carriage is moved 125 away from said tools, and to draw a piece of stock through the space between the decorticating tools of the other set as the carriage is moved in the reverse direction.

7. A machine of the class described com- 130

prising in combination a main frame having a longitudinally extending track, a carriage mounted upon said track, means for reciprocating said carriage along said track, stock located at each end of the path of travel of said carriage, gripping jaws at each end of the carriage, of said jaws means constructed so as to hold the jaws at one end of the carriage in gripping position while the jaws at the other end of the carriage are allowed to remain open, and decorticating tools carried on the frame and located at each end of the path of travel of said jaws.

PATRICK HENRY FRANK.
